UNITED STATES PATENT OFFICE.

HAROLD L. CHILDS, OF ELYRIA, OHIO.

COMBINATION TABLE.

Application filed July 16, 1923. Serial No. 651,766.

This invention relates to improvements in a combination table.

An object of my invention is to provide a structure which can be used either as an ordinary table, or as a support for a sewing machine head.

Another object of my invention is to provide a collapsible table, constructed to permit the legs to be folded beneath the table 10 top when not being used.

Another object of my invention resides in the manner in which the legs of the table are secured to provide a solid support for the top.

15 These and other objects will appear hereinafter.

In the accompanying drawings, which illustrate my invention,

Fig. 1 is a top plan view of my improved table showing an opening into which a sewing machine can be seated.

Fig. 2 is a side elevation of the same.

Fig. 3 is a front view of the same.

Fig. 4 is a rear view of the same.

25 Fig. 5 is a top plane of the table with the cover in place to provide a smooth top.

Fig. 6 is a fragmentary view showing the manner in which the panels are secured to the table.

30 Fig. 7 is a section taken on line A—A of Fig. 5.

Fig. 8 is a fragmentary view showing the manner of securing the table legs, and

35 Fig. 9 is a front elevation of the table with the legs folded.

Referring to the drawings, which illustrate an embodiment of my invention, by characters of reference the table frame is shown consisting of side members 10 and 40 end members 11 secured together. The frame illustrated is rectangular, but it can be constructed in other shapes if desired. A top 12 extends over and is secured upon the upper portion of the frame.

45 The frame is supported upon two pairs of legs 13 and 14, which are secured one at each end of the frame. Each pair of legs are secured rigidly together by transversely extending members 15 which extend therebetween. The pairs of legs are hinged at 16 and 17 to the inner side of the end members of the frame and are positioned in different horizontal planes so that they can be 50 swung inwardly into the frame, one beneath the other when desired, and the ends thereof are arranged to extend under and sup-

port the lower edge of the end members of the frame when extended.

Panels 18 and 19 are hinged at 20 and 21 respectively to the inside wall of one of 60 the side members of the frame and adjacent the ends thereof. The panels are arranged to swing into the frame above the pairs of legs when folded up. When the legs and panels are unfolded and extend from the 65 frame, the panels project downwardly adjacent the legs and suitable releasable connections 22, such as a hinged hook and an eye bolt, are provided to secure the legs to the lower portion of the panels. In this 70 manner the legs are maintained in extended position and rigidly support the frame.

The top 12 is provided with a rectangular opening 24 therethrough to receive a sewing machine head. Braces 25 and 26 extend 75 across the frame, under the opening 24 and are secured at their ends to the inner wall of the side members of the frame. These braces serve as supports upon which the sewing machine head rests when placed 80 within the opening in the table top. The edges of the top adjacent the opening are provided with seats 27.

When the sewing machine head is removed from the opening in the top, a cover 85 28 may be inserted into the opening. The cover is of substantially the same shape as the opening and is provided with shoulders 29 which rest upon the seats 27 in the top, to maintain the top of the cover flush with 90 the upper face of the table top. The cover 28 is provided with a countersunk bracket 30 having a raised portion 31 under which the operator can insert his finger to readily remove the cover from the top.

95 It will be noted that by inserting or removing the cover either an ordinary table having an unbroken surface, or a sewing table may be readily provided. The legs of the table are connected so that they can be 100 readily folded to provide a compact structure when the table is not in use, and means for forming a rigid vibrationless support for the frame can readily be formed when the legs are extended.

105 Various changes can be made in the details of construction illustrated and described without departing from the spirit of my invention and the scope of the claims.

What I claim is:

110 1. In a convertible table, a top having an opening therethrough, the walls of the open-

ing being cut inwardly from the opening at intervals to form seats around the edges of the opening, and a freely removable cover adapted to be inserted within the opening in said top to provide an uninterrupted top surface, said cover having laterally extending supporting shoulders extending therefrom at intervals and arranged to extend into said seats formed in said top.

10 2. In a convertible table, a top having an opening therethrough, the walls of the opening being cut inwardly from the opening at intervals to form seats around the edges of the opening, and a freely removable cover adapted to be inserted within the opening in said top to provide an uninterrupted top surface, said cover having laterally extending supporting shoulders extending therefrom at intervals and arranged to 20 extend into said seats formed in said top, and a countersunk bracket secured within the top of said cover by which said cover may be lifted from the opening in the top.

15 3. In a table, a top having an opening

therethrough and seats formed around the edges of the opening, and a freely removable cover for said opening, said cover being provided with laterally extending supporting shoulders for engagement with said seats when the cover is placed within the opening, said cover forming an uninterrupted surface with said table top when in position.

4. In a table, a top having a rectangular opening therethrough and pockets formed around the edges of the opening, a freely removable cover for said opening, said cover forming an uninterrupted surface with said top when in position, said cover having supporting shoulders adapted to rest in said pockets when the cover is placed within the opening of the top, and cross braces near the ends of said rectangular opening and below the top thereof.

In witness whereof, I hereunto affix my ⁴⁵ signature this 13 day of July, 1923.

HAROLD L. CHILDS.
